CLAIM

The ornamental design for left and right front side portions of an outer shell of a sports helmet, as shown and described.

DESCRIPTION

FIG. 1 is a front perspective view of left and right front side portions of an outer shell of a sports helmet, showing our new design;

FIG. 2 is a rear perspective view of the left and right front side portions of FIG. 1;

FIG. 3 is a front elevational view of the left and right front side portions of FIG. 1;

FIG. 4 is a side elevational view of the left and right front side portions of FIG. 1; and,

FIG. 5 is a side elevational view of the left and right front side portions of FIG. 1, opposite that of FIG. 4.

The broken lines form no part of the design and are for illustrative purposes only.
